Attorney

UNITED STATES PATENT OFFICE

ROBERT S. BACHELER, OF BALTIMORE, MARYLAND

HEAT DIVERTER

Application filed August 16, 1929. Serial No. 386,383.

This invention relates to a heat diverter and more particularly to a flue cover and deflector of the type generally associated with the flue collar or stack of a gas cooking range for the purpose of covering the top of the flue or stack and deflecting the gases comprising the products of combustion in a downwardly and forwardly direction whereby their tendency to be deposited on the walls and neighboring objects is reduced to a minimum.

The object of this invention is to provide a heat diverter that may be easily attached to a flue, and also easily demountable with respect thereto for purposes of cleaning or replacing the same, said heat diverter being of an inverted trough shaped form and provided with spaced longitudinally positioned openings in the front of said heat diverter to facilitate the discharge of the products of combustion gently and without violence and discomfort in a downwardly and forwardly direction.

Other objects of this invention will become apparent as the description thereof proceeds, reference being now had to the accompanying drawing wherein:

Figure 1, is a front elevational view of the heat diverter and a portion of the flue or stack, and

Figure 2, is a sectional view of the same taken on line 2—2, Figure 1.

The heat diverter or deflector 1, is preferably a metal casting of an inverted trough shaped form and comprises a top 2, side walls 3, back 4, and front wall 5. The side walls 3 are formed identical to each other and connect the back 4 and front wall 5, which are of two different convex curvatures merging together at their upper ends to form the curved convex top 2. As is apparent from Figure 2, the radius of curvature of the back 4 is less than the radius of curvature of the front wall 5.

Positioned substantially midway between the back 4 and front wall 5 and parallel with the back 4 is a partition 6, the ends of which merge with the inner surface of the side walls 3, that are of concave curvature, 50 to form with the back 4 a substantially oval

shaped opening 7 which is adapted to fit over a similarly conventional shaped flue collar 8 of a flue or stack 9.

Formed in the front wall 5 are two spaced longitudinally disposed slots or openings 10, 55 extending substantially the full length of said front wall. The upper and lower walls 11 and 12, respectively, of each of the slots or openings 10 are parallel to each other and are arranged diagonally with respect to the vertical, as clearly shown in Figure 2.

As the flue gases or products of combustion are discharged through the top of the flue or stack 9, they are deflected downwardly due to the interiorly curved surface of the heat diverter 1, and are discharged through the opening 7', which incidentally is of substantially the same area as the opening 7, and also forwardly through the openings 10, in the front wall 5. Due to the provision of the openings 10, the products of combustion are diffused gently into the air at a high level when discharged, thereby obviating the objectional blast or forceful flow of said gases in a downwardly direction through the discharge opening 7' usually felt by a person working at a gas range.

While a preferred embodiment of the invention has been disclosed, it is to be understood that the same is susceptible of various modifications within the scope of the appended claims.

Having thus described my invention, what I claim as new and desire to secure by Letters Patent is:

1. A flue cover and heat diverter embodying, an inverted trough shaped casing comprising a top of varying convex curvature, the radius of curvature of the rear portion thereof being less than the radius of curvature of the front portion thereof, side walls integral with said top, a partition of a height less than one-half of said flue cover, integrally attached to said side walls adjacent the bottom thereof and dividing said bottom into two openings of substantially equal area, the opening at the rear of said flue cover being adapted to receive therein the flue collar of a flue, and a plurality of spaced longitudinally disposed slots formed in the front portion

of said top and, extending through the same in a diagonally downward direction.

2. A flue attachment for gas stoves having a substantially horizontal discharge opening substantially coequal in area to the flue opening, comprising a substantially semi-cylindrical hood having a substantially semi-cylindrical peripheral wall and substantially flat end walls merging thereinto, the edge portions of the walls being in the same horizontal plane and presenting a substantially rectangular opening, a partition strip extending between the end walls and dividing the opening into two parts substantially coequal in area, and a stack, or pipe, for supporting the hood a distance above the flue outlet of a stove, said stack having one end associated with the flue outlet flange of the stove and its opposite end held in one of the last named parts between said strip and the lower rear edge portion of the peripheral wall, the front portion of said peripheral wall a substantial distance above the bottom edge of the same being provided with an outlet opening.
- 15 3. A flue attachment for gas stoves including a hood having a substantially semi-cylindrical peripheral wall and substantially flat end walls merging thereinto, the marginal edge portions of the walls presenting a substantially rectangular opening, a strip extending between the end walls and dividing the opening into two parts, and a stack, or pipe, having one end associated with the flue opening of the gas stove and its opposite end held in one of the last named parts between said strip and the lower rear edge portion of the peripheral wall, the front portion of said peripheral wall a substantial distance above the bottom edge of the same being provided with a plurality of outlet openings.
- 20 4. A flue attachment for gas stoves comprising a hood having a substantially semi-cylindrical peripheral wall and end walls merging thereinto, the marginal edge portions of the hood presenting a substantially rectangular opening, a partition extending between the end walls substantially midway between the front and rear marginal edge portions of the peripheral wall, and a pipe having one end adapted to be associated with the flue opening of a gas stove and having its opposite end held between said partition and the lower rear edge portion of the peripheral wall, the front portion of said peripheral wall a substantial distance above the bottom edge of the same being provided with a horizontal slit.
- 25 5. A flue attachment for gas stoves comprising a hood having a substantially semi-cylindrical peripheral wall and end walls merging thereinto, the marginal edge portions of the hood presenting a substantially rectangular opening, a partition extending between the end walls substantially midway

between the front and rear marginal edge portions of the peripheral wall, and a pipe having one end adapted to be associated with the flue opening of a gas stove and having its opposite end held between said partition and the lower rear edge portion of the peripheral wall, the front portion of said peripheral wall a substantial distance above the bottom edge of the same being provided with a plurality of horizontal slits having downwardly and outwardly inclined wall surfaces.

In testimony whereof I affix my signature.

ROBERT S. BACHELER.
